Primary Examiner — John Windmuller*Assistant Examiner* — Luqman McNeil(74) *Attorney, Agent, or Firm* — Paul M. Denk(57) **CLAIM**

The ornamental design for the nozzle adaptor, as shown and described.

DESCRIPTION

FIG. 1 provides a side view of the nozzle adaptor of this invention;

FIG. 2 is a top view;

FIG. 3 is an opposite side view;

FIG. 4 is a bottom view;

FIG. 5 is a back view; and,

FIG. 6 is a front view.
